CLAIM

We claim the ornamental design for a wheel hub cap, as shown and described.

DESCRIPTION

FIG. 1 is a front view of a wheel hub cap, showing our new design, shown in its position of use;

FIG. 2 is a front perspective view thereof;

FIG. 3 is a front view of the wheel hub cap of FIG. 1 with the tire removed;

FIG. 4 is a side view of FIG. 3;

FIG. 5 is a front perspective view of FIG. 3;

FIG. 6 is a front view of a second embodiment of a wheel hub cap, showing our new design, shown in its position of use;

FIG. 7 is a front perspective view of FIG. 6;

FIG. 8 is a front view of the wheel hub cap of FIG. 6 with the tire removed;

FIG. 9 is a side view of FIG. 8; and,

FIG. 10 is a front perspective view of FIG. 8.

The broken line showing of the tire in FIGS. 1, 2, 6 and 7 depict environmental subject matter and form no part of the claimed design. The portions of the wheel hub cap in the figures shown in lighter lines represent contour.
